UNITED STATES PATENT OFFICE.

WARD B. HAUSMAN, OF PHILADELPHIA, PENNSYLVANIA.

TOBACCO-PIPE CLEANER.

SPECIFICATION forming part of Letters Patent No. 606,716, dated July 5, 1898.

Application filed August 31, 1897. Serial No. 650,078. (No model.)

To all whom it may concern:

Be it known that I, WARD B. HAUSMAN, a citizen of the United States, residing at Philadelphia, in the county of Philadelphia and State of Pennsylvania, have invented a certain new and useful Improvement in Tobacco-Pipe Cleaners, of which the following is a specification.

My invention relates to a new and useful improvement in tobacco-pipe cleaners, and has for its object to provide a simple, cheap, and effective device of this description which when applied to a pipe or the stem thereof will cause the smoke passing through the bowl of the pipe to travel a circuitous route of such length as to not only cool the smoke, but precipitate the surplus nicotine which may be suspended therein; and a further object of my invention is to provide for the cleaning of the pipe-stem by simply withdrawing the arrester, and when this does not satisfactorily perform the desired result said arrester may be turned upon its axis while being withdrawn to further precipitate the accomplishment thereof.

With these ends in view this invention consists in the details of construction and combination of elements hereinafter set forth, and then specifically designated by the claim.

In order that those skilled in the art to which this invention appertains may understand how to make and use the same, its construction and operation will now be described in detail, referring to the accompanying drawing, forming a part of this specification, in which I have shown a central section of a pipe having my improvement applied to both the stem and mouthpiece thereof.

In carrying out my invention as shown in the drawing, A represents the pipe-bowl, and B the stem, through which latter is formed an opening of considerable size, which connects with the bowl, as indicated at C. A plug D, adapted to screw within the outer end of the stem, has formed therewith or secured thereto the arrester and cleaner E, which latter consists of a core having a deep slow-pitched thread formed thereabout, as clearly shown, and the outer circumference of this thread snugly fits within the opening of the

stem, so that all draft drawn through the pipe-stem will be caused to pass around and around the groove formed by the thread until reaching the plug, through which it will pass by means of the hole F, formed therein. 55

The mouthpiece G is arranged to be secured to the plug by means of the threaded shank H, and this threaded shank has formed therewith a screw-like arrester and cleaner I of smaller dimensions than the arrester E, so 60 that after the smoke has passed through the plug and shank it will be again caused to wind its way around the groove formed by the threads upon the arrester I until reaching the exit J in the mouthpiece. 65

From this description it will be obvious that the smoke drawn from the bowl of the pipe will be considerably cooled in its passage to the mouth of the smoker, and at the same time a large percentage of the nicotine suspended therein will be precipitated in the windings of the smoke in gaining access to the exit. 70

After the pipe has been used sufficiently to produce a considerable deposit of nicotine the 75 stem may be cleaned by unscrewing the plug, whereupon the core of the arrester and cleaner will be turned and the edge thereof will scrape the walls of the stem, the thread acting after the manner of a screw conveyer to remove the 80 deposit at the same time that it is scraped from the walls.

If it is desired only to clean the mouthpiece, it alone is unscrewed from the plug, when the screw-thread upon the shank will scrape the 85 passage through said mouthpiece, the operation being in every way similar to that described in connection with the cleaning of the stem.

Having thus fully described my invention, 90 what I claim as new and useful is—

In combination with a pipe, a plug threaded in the end of the stem thereof, a cleaner consisting of a core formed with the plug, a slow-pitched thread formed thereabout and fitting 95 against the walls of the passage within the stem, whereby when the plug is unscrewed the edges of the thread will scrape said walls, a threaded shank partly screwed within said plug, a cleaner similar to the first named 100

formed with said shank and a mouthpiece
threaded to said shank, the cleaner fitting
within the passage thereof, whereby when the
mouthpiece is unscrewed the cleaner will act
5 after the manner of a screw conveyer and
scrape the walls of the passage, as and for the
purpose set forth.

In testimony whereof I have hereunto af-
fixed my signature in the presence of two sub-
scribing witnesses.

WARD B. HAUSMAN.
